DISPLAY APPARATUS

Oxford Douglas McNeill, Forest Hill, Ontario,
Canada, assignor to Colgate-Palmolive-Peet
Company, Jersey City, N. J., a corporation of
Delaware

Application June 1, 1950, Serial No. 165,443
In Canada May 16, 1950

3 Claims. (Cl. 40—126)

1

This invention relates to apparatus for displaying the foaming qualities of detergent material particularly for advertising displays.

An object of the invention is to provide an apparatus which is capable of continuous operation with a limited quantity of detergent and solvent liquid.

A further object of the invention is to provide apparatus which may readily be set up in a confined space, such as a store display window and be operated with a minimum of soilage notwithstanding the continual collapse and regeneration of a substantial quantity of foam.

Broadly, the invention consists in a tank for containing a foam-producing liquid and foam produced therefrom, the tank having at least one wall including a transparent panel through which the contents may be viewed, a port in the tank for withdrawing liquid therefrom, a conduit for delivering liquid to the tank, an outlet to the conduit arranged to direct liquid downwardly within the tank, a pump connected between the port and the conduit and arranged to deliver liquid under pressure to the outlet, and means for driving the pump.

In the operation of the apparatus, foam is generated by the stream of liquid directed from the outlet into the tank and is continuously replenished as it collapses due to drainage into the tank. The generated foam is, moreover, effectively displayed through the transparent panel of the tank, all the walls of which may be transparent if desired, the walls of the tank being made high enough to contain the body of foam which results from the use of a predetermined quantity of detergent and liquid at the pump pressure involved.

The liquid is also continuously withdrawn from and resupplied to the tank in a closed circuit so providing an equipment specially suited to a window display.

Preferably, the drainage port is located in the bottom of the tank, the conduit extending upwards within the tank from the bottom thereof for a substantial distance to a reversely bent portion directed towards the bottom.

To assist in the generation of foam, the outlet from the conduit preferably includes means for aerating liquid passing therethrough; this may conveniently take the form of a nozzle detachably secured to the conduit, having an internal bore communicating with the conduit and a narrow passage intermediate the ends of the bore which extends completely through the wall of the nozzle and opens into the bore and slants towards the bore in the direction of flow of the liquid therethrough.

2

A specific embodiment of the invention will now be described, by way of example, with reference to the accompanying drawings in which:

Figure 1 is a top plan view of the apparatus,
5 Figure 2 is a front elevation,
Figure 3 is a detail of the outlet nozzle, and
Figure 4 is a further detail.
The display apparatus has a rectangular base
11 made, for example, of plywood in the form of
10 a box having an open bottom and a top closed
by a water-proof partition 12, for example, of
water-proof plywood, which extends beyond the
outline of the base on all sides as shown. The
partition 12 forms the bottom of a transparent
15 tank of about the same depth as the base 11, the
tank comprising a rectangular frame 13, for ex-
ample of 2 x 4 inch wood, glued and screwed to
the partition 12 in a water-tight manner, and
vertical side walls 14 of transparent material
20 which are abutted end to end and are set with
their lower edges held within longitudinal chan-
nels in the upper sides of the frame members 13.
The side walls 14 may be made of glass but pref-
erably consist of $\frac{1}{4}$ " thick Plexiglas and are se-
25 cured together by corner members 15 which may
conveniently be made of aluminium. The joints
between the walls 14, corners 15 and frame 13 are
all water-tight.

Secured to the underside of the partition 12 is
30 an electric motor 16 and a gear water pump 17 in
driving engagement therewith through a belt 18.
A drainage port 19 is provided centrally in the
partition 12 and connects through a pipe 20 and
a manual control valve 26 of variable opening
35 to the inlet of the gear pump. The outlet of the
gear pump is connected to a pipe 21 which passes
through the partition 12 in a water-tight joint
and terminates in a fluid tight coupling 22. A
liquid delivery conduit 23 preferably of chro-
40 mium plated brass is connected to the coupling
22 and extends upwards within and beyond the
walls 14 of the tank, the total length of the con-
duit 23 being approximately three times the depth
of the walls 14. The upper end of the conduit 22
45 is bent into a U shape, in the down-turned end
of which a nozzle 24 (shown in detail in Figure
3) is detachably secured through an external
screw thread engaged with an internal thread in
the end of the conduit. The nozzle 24 has a small
50 axial bore 25, conveniently made by a No. 18 twist
drill—diameter 0.1695 inch—which is small as
compared with the internal diameter of the con-
duit 22 and is provided with a fine passage 26 in-
termediate the ends of the bore 25 which extends
55 through the wall of the nozzle and opens into the
bore. Passage 26 may conveniently be made by a

No. 43 drill—diameter 0.0890 inch—drilled at an angle of 60° to the axis of the bore 25 and at a distance, measured along the outside of the nozzle, of about $\frac{3}{8}$ " from the bottom end thereof so that the passage slants towards the bore in the direction of flow of liquid therethrough.

During the flow of liquid downwardly through the nozzle 24, air is aspirated through the passage 26 and the liquid issuing from the nozzle is accordingly aerated.

Close to the coupling 22, the conduit 23 is provided with three narrow horizontal spray holes 27, see Figure 4, which extend radially through the conduit and are directed rearwardly of the apparatus, the holes 27 being spaced apart by approximately 60°. The holes 27 may conveniently be made with a No. 43 twist drill and serve to direct a fine spray of liquid across the tank in the general direction of the drainage port 19.

A U-shaped bracket 28 is mounted on the partition 12 rearwardly of the outlet port 19 and serves to support a large package 29 having a "get-up" simulating the commercial packages of the detergent product being advertised.

In the operation of the device, the motor 16 drives the gear pump 17 to withdraw from the tank through the outlet 19 liquid in which a detergent is dissolved and to return it to the tank through the nozzle 24. The quantity of aerated liquid issuing per unit time through the nozzle 24 is controlled by the valve 20' so that a large body of foam builds up within the tank which is displayed through the side walls 14 as indicated in outline at 30 in Figure 2. The spray holes 27 supply a continuous liquid spray through the body of foam 30 so effecting dynamic stabilisation of the foam at a height within the tank which may be predetermined by the setting of the valve 20'. By this means the foam 30 which is continuously drying by evaporation is continuously cut down, dissolved and returned to the circuit and any tendency for the foam to rise continuously within the tank and eventually to overflow the boundaries thereof is effectively prevented. In place of, or in addition to, the control valve 20' which controls the inlet to the pump 17, the delivery side of the pump may be provided with a variable by-pass, as shown in chain-line in Figure 1, comprising a branch conduit 31 controlled by a manual valve 32 of variable opening.

With a tank having an internal length of 42 inches and an internal width of 30 inches, it is found that a pail and a half of water and a tablespoon of household detergent, such as that commercially available under the registered trademark "FAB," is effective to provide a continuous body of foam for a substantial time. The water should, of course, be replenished from time to time to make up for loss by evaporation.

What I claim as my invention is:

1. Apparatus for displaying the foaming properties of detergent materials which comprises a tank adapted to contain a foam-producing liquid and foam produced therefrom, said tank having at least one wall including a transparent panel

through which the contents may be viewed, a drainage port in the bottom of said tank for withdrawing liquid therefrom, a conduit extending into said tank through the bottom thereof having a duct extending longitudinally therethrough for delivering liquid to said tank, said conduit terminating in an outlet arranged to direct liquid downwardly in said tank, a plurality of spray holes extending radially through the wall of said conduit and communicating with the duct therein, said spray holes being arranged in operative relationship within said conduit and near the bottom of the tank to spray liquid delivered thereto across said tank and through the foam contained therein to break down the foam and prevent the same from overflowing the tank, and a power actuated pump disposed in operative relationship between said port and said conduit and arranged to deliver liquid under pressure in said outlet.

2. Apparatus as set forth in claim 1 in which said outlet comprises a nozzle secured to said conduit, said nozzle having an internal bore communicating with the duct in said conduit and a narrow passage intermediate the ends of said bore which extends completely through the wall of the nozzle and opens into said bore, the bore of said nozzle having a diameter less than the diameter of the duct of said conduit.

3. An advertising device for exhibiting the foaming qualities of a detergent material comprising, display means simulating commercial packages of the detergent being advertised, a tank for containing a foaming liquid, said tank having at least one wall including a transparent panel through which the contents may be viewed, a drainage port in said tank for withdrawing liquid therefrom, a conduit having a duct extending longitudinally therethrough for delivering liquid to said tank, said conduit extending upwardly within said tank from the bottom thereof for a substantial distance to a reversely bent portion terminating in an outlet adapted to direct liquid downwardly within said tank, said outlet including means for aerating liquid passing therethrough, said conduit having a plurality of spray holes extending radially through the wall thereof and communicating with the duct therein, said spray holes being arranged in operative relationship within said conduit near the bottom of the tank to spray liquid delivered thereto across said tank and through the foam contained therein to break down the foam and prevent the same from overflowing the tank, and a power actuated pump disposed in operative relationship between said port and said conduit and arranged to deliver liquid under pressure to said outlet.
